UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

YARN SPOOL.

Application filed February 15, 1927. Serial No. 168,324.

This invention relates to yarn spools, particularly the type used in Axminster tube frames in which a disappearing or retractile pindle is used for a supporting journal 5 in order to facilitate the removal of the spool from its bearings. One object of the invention is to provide an all-metal spool of light, strong and durable construction which can be easily made and assembled and which 10 may be easily disassembled for replacement of the spring or pindle in case of injury or breakage of either of these parts.

In the specific embodiment of this invention illustrated in the drawings the yarn-spool 15 embraces a tubular barrel having an end head provided with an interior offset annular shoulder fitting inside the barrel, and carrying an axially disposed gudgeon in which is slidably mounted an axial bearing 20 pindle which is normally spring pressed outward by a spring whose inner end is seated against a thrust member that is detachably secured to the gudgeon and which may also, if desired, form a rearward bearing for the 25 pindle in order to provide a long bearing support therefor. These and other features of the invention will be particularly described in the following specification and will be defined in the claims hereto annexed.

In the accompanying drawings I have illustrated one form of construction and arrangement embodying the principles of this 30 invention, in which:

Figure 1 is a plan view chiefly in central section to expose the interior construction 35 of the spool.

Figure 2 is a side elevation of the detachably interlocked thrust member.

Figure 3 is an end view of the thrust 40 member.

Figure 4 is an elevation of the attaching member that locks the thrust member to the spring structure.

Figure 5 is an edgewise view of said attaching member as seen at right angles to the axis of the spool.

In the practice of this invention, according to the form illustrated, a tubular metallic barrel 4 is provided and into each end thereof is inserted the offset interior hub portion 2, of an end head 1, which fits snugly inside the end of the tubular barrel and is secured thereto by soldering or any other suitable manner. The inner edge portion of

the outer shoulder is turned inward to form 55 a flat flange portion 3, which is centrally perforated to permit the insertion of a suitable shouldered bearing gudgeon.

As it is unnecessary that both ends of the spool should have a retractile pindle or journal, the fixed journal at one end comprises a shouldered head 10, inserted through the flat annular flange 3, with its inner end 10^a headed over the edge of the flange or, in this case as actually shown, over the head 60 of a stiffening washer 9, while the outer end 65 of the gudgeon 10 is reduced, as shown at 10^a, to form a pindle journal.

At the opposite end of the spool the turned centrally bored flange 3 receives a 70 shouldered gudgeon 5 to which it is secured in a somewhat similar fashion. This gudgeon, however, is centrally bored to receive a 75 slidingly mounted elongated pindle 6, provided with a stop shoulder 6^a, against which presses an outwardly thrusting helical spring 6^b.

To provide a convenient means for sustaining the inward thrust of the pindle spring 6^b, I provide a thrust member 8 of 80 novel construction intended to be detachably locked to the gudgeon or spool structure at its outer end so as to permit easy replacement of the spring or the pindle in case of 85 injury to either.

This thrust member 8 has a longitudinal body portion terminating in two substantially right angled wings 8^a and 8^b, the former of which is cut away, as shown in Figure 3, to form the wing into attaching 90 jaws. The latter wing 8^a is perforated, the perforation preferably being dimensioned to form a bearing opening for the inner end 95 of the pindle 6, and affords a seat for sustaining the thrust of the inner end of the pindle 95 spring 6^b.

For stiffening purposes a washer 9, surrounding the neck of the gudgeon 5, is preferably employed and on the inner side of said washer an attaching member 7 is placed 100 for the purpose of interlocking the thrust member 8 to the gudgeon and spool. This attaching member comprises a center washer-like body portion 7, adapted to fit snugly over the neck of the gudgeon 5, and having on opposite sides offset projecting wings 7^a. The center portion is dimensioned to 105 allow the jaws 8^a of the thrust member to

straddle when the jaws are inserted between the offset locking lips 7^a and the adjacent plane surface of the stiffening washer 9.

The gudgeon is fastened in place after its neck portion has been inserted through the flange 3, the washer 9, when such washer is used, and the locking washer 7, and the end of gudgeon is then headed over the edge of the washer 7 to hold these three members firmly together and thereby rigidly support the gudgeon in its axial position. The pintle, with its surrounding spring, is then inserted through the gudgeon and the thrust member placed with its inner wing 8^b surrounding the inner end of the pintle after which it may be moved along the pintle to compress the spring and hook its spaced jaws 8^a between the wing 7^a of the washer 7 and the adjacent face of the washer 9. Having been thus assembled the head with its connected parts is inserted inside the hollow end of the tube and there soldered in place.

In case of injury to the spring or pintle the head may be unsoldered and withdrawn, the thrust member may then be disengaged from the wings of the attaching member to permit the withdrawal of the spring and of the pintle and their replacement. The thrust member may be given any desired length to accommodate any desired length of thrust spring, and may conveniently serve as an inner bearing support having a long leverage engagement with the inner end of the pintle to aid in preserving its axial alignment. It will be observed that when the assembled parts are inserted and secured in the barrel that displacement of the thrust member is impossible by reason of the engagement of the flat transverse body portion 8 with the flat edge portion of the washer 7. The parts being confined within the barrel, the rotation of the thrust member relative to the attaching washer is prevented by this engagement.

What I claim is:

1. In a yarn spool, the combination with a tubular barrel, an end head having an interior annular hub portion with an inwardly turned centrally perforated flange, an axially disposed longitudinally bored gudgeon having its inner end portion reduced to form a neck fitting into the aperture in said flange, a spring pressed pintle slidably in said bore, an attaching member also surrounding the inner end of the gudgeon and having pe-

ripheral laterally offset wings, a thrust member having at its outer end detachable locking engagement with said wings and having a transverse portion arranged to form a seat for sustaining the inner end of the pintle-pressing spring.

2. In a yarn spool, the combination with a tubular barrel, a transverse end head secured thereto, an axially disposed longitudinally bored gudgeon rigidly secured in a central aperture in said end head to project through the aperture, an axially slidable pintle mounted in said bore of the gudgeon, a helical spring acting to normally press said pintle outward to normal spool-supporting position, and a thrust member detachably secured to the inner end of the gudgeon and affording at its inner end a seat for the inner end of the spring to support the thrust thereof.

3. In a yarn spool, the combination with a tubular barrel and a transverse disk-like head rigidly secured thereto, an axially disposed axially bored gudgeon firmly secured in a central aperture of said head, an axial shouldered pintle slidably mounted in said gudgeon bore and a spring normally pressing said pintle outward, a thrust member projecting inwardly from the inner end of said gudgeon and having at its outer end attaching jaws arranged to detachably interlock with coordinated locking wings rigidly secured to the inner end of the gudgeon and having, at its rear end, a transverse member bored to receive the inner end of the pintle and forming a thrust seat for the inner end of the pintle spring.

4. In a yarn-spool for tube frames or the like, the combination with a barrel, of an end head provided with an interiorly located axially offset centrally perforated hub portion securely fastened in a hollow end of the barrel, an axially bored gudgeon whose inner end is inserted through the aperture in said hub and is provided with opposing shoulders on opposite sides of the hub preventing its axial displacement, a spring-pressed pintle slidably mounted in the bore of said gudgeon, and a thrust member interlockingly connected with and supported by said hub projecting inwardly therefrom in position to sustain the inward thrust of the pintle-actuating spring.

In witness whereof, I have subscribed the above specification.

EDGAR F. HATHAWAY.
